FLUID APPARATUS

Earl Cannon, Downers Grove, and Edward J. Lukes, Brookfield, Ill., assignors to American Steel Foundries, Chicago, Ill., a corporation of New Jersey

Application October 2, 1947, Serial No. 777,548

14 Claims. (Cl. 103—5)

1

This invention relates to hydraulic systems and more particularly to a novel system for supplying hydraulic fluid at a predetermined adjustable pressure as, for example, to a vessel for testing the same.

It has been found that in pressure vessel testing apparatus utilizing an hydraulic medium, such as oil, a wide range of selectivity in the pressure is frequently desirable, necessitating the use of a multiplicity of relief valves adapted to be selectively connected to the pressure line for regulating the hydraulic pressure therein. Furthermore, in such an apparatus the pressure must be maintained by a source, such as a pump, against the relief valve resulting in excessive wearing thereof and in excessive power consumption by the pump.

An object of the present invention is to design a novel system, such as above-described, wherein the desired pressure is maintained by a pneumatic intensifier device thereby eliminating the necessity of holding the pressure against a relief valve.

Another object of the invention is to afford adjustability of the pressure in the system by providing in series a plurality of air intensifier devices, one or more of which may be actuated to adjustably vary the pressure of the hydraulic fluid supplied by the system.

Still another object of the invention is to provide means for automatically recharging the system when the volume of hydraulic fluid reaches a predetermined minimum value.

The foregoing and other objects and advantages of the invention will become apparent from a consideration of the following specification and the accompanying drawings, wherein the single figure illustrated is a flow diagram of the hydraulic system, portions of the apparatus being shown in central vertical cross section, and a wiring diagram of the electrical actuating system associated with the hydraulic system.

Describing the invention in detail and referring to the drawing which illustrates the invention embodied in a pressure vessel testing apparatus. The system includes a supply line 2 connected to the vessel 4 to be tested. The line 2 is provided with a pressure gauge 6 and conventional stop cocks 8.

The line 2 is connected through a check valve 10 to an hydraulic cylinder 12 containing a ram 14 adapted to exert a predetermined adjustable pressure against the fluid in the cylinder 12 and the line 2. The ram 14 is actuated by one or both of a pair of gas pressure intensifier devices, 55

2

generally designated 15 and 16. The device 15 comprises a piston 18 carrying a rod 20, one end of which is engageable with the ram 14, the opposite end of the rod being engageable with a rod 22 connected to a piston 24 reciprocal within a cylinder 26 of the device 16.

Compressed gas, such as air, is conveyed to the devices 15 and 16 by a line 28 having a branch 30 connected to the cylinder 17 and a branch 32 connected to the cylinder 26 through a selector valve 34 adapted to connect the cylinder 26 to the line 28 or to exhaust line 36. The line 28 is preferably provided with a gauge 39 and a conventional pressure reducing valve 40.

Preferably the pressure area of the piston 18 in the cylinder 17 is from about one-fifth to one-sixth of the pressure area of the piston 24. Therefore, when low pressures are desired, only the device 15 is actuated, and the reducer valve 20 40 is adjusted to maintain a predetermined pressure value in the line 30, thereby maintaining pressure within a range of from, for example, fifty to three hundred pounds pressure per square inch on the hydraulic fluid within the cylinder 12. When higher pressures are desired, both devices 15 and 16 are actuated affording an adjustable pressure range of from, for example, three hundred to fifteen hundred pounds per square inch on the fluid within the cylinder 12.

By means of this arrangement an adjustable range of pressures within the cylinder 12 are provided within a ratio of thirty to one, and it will be understood by those skilled in the art that such a range would be unfeasible with any conventional reducer valve 40. Furthermore, the above-described arrangement affords a relatively simple means for adjusting the pressure within the cylinder 12 without the necessity of resorting to complicated and expensive valve mechanisms.

The cylinder 12 is automatically charged by a pump 42 operated by a motor 44. The discharge side of the pump 42 is connected to a line 46 having a conventional safety relief valve 48 adapted to discharge at a predetermined maximum pressure value through a relief line 49 to a reservoir 51 connected by a line 53 to the suction side of the pump 42. The valve 48 is adapted to function as a safety relief valve to prevent the building up of dangerous pressures by the pump 42 in the event of improper functioning of the actuating system for the pump, as herein-after described.

In operation of the novel system, when the volume of fluid in the cylinder 12 is at or below a pre-

determined minimum value, a rod 52 carried by the ram 14 closes a normally open switch 54 thereby closing a circuit through a solenoid coil 56 of a normally open double relay 58. Thus the coil 56 is energized by a conventional voltage supply 60 having one terminal connected to ground as at 61 and the other terminal connected to one end of the coil. The opposite end of the coil is connected to one contact of the switch 54, the other contact of which is connected to ground as at 63 thereby closing a circuit through the coil 56 as the switch 54 is closed.

Energization of the coil 56 closes the relay 58 thereby closing a holding circuit through the coil 56 and a normally closed switch 62 and another circuit through the motor 44 which is thereby actuated by a conventional voltage supply 64.

As the motor 44 is energized, the pump 42 charges the cylinder 12 until the arm 52 engages the switch 62 thereby opening the same and de-energizing the coil 56 whereupon the relay 58 is opened breaking the holding circuit through the coil and also breaking the circuit through the motor 44 to stop the pump 42. Makeup fluid is supplied to the line 2 by the cylinder 12 which is recharged, as above described, when the switch 54 is again closed as the volume of pressure fluid in the cylinder 12 reaches the predetermined minimum value at which the arm 52 engages the switch 54.

It will be understood by those skilled in the art that, if desired, the motor 44 and pump 42 may operate continuously and the above-mentioned electrical control circuits may be connected, for example, to the valve 48 for actuation of the latter to by-pass the output of the pump 42 upon opening of the switch 62 and to deliver the output of the pump 42 to the line 46 upon closing of the switch 54.

It is to be understood that we do not wish to be limited by the exact embodiment of the device shown which is merely by way of illustration and not limitation as various and other forms of the device will, of course, be apparent to those skilled in the art without departing from the spirit of the invention or the scope of the claims.

We claim:

1. An hydraulic system for supplying hydraulic fluid under a predetermined pressure comprising an hydraulic cylinder, a ram therein, means for developing pressure against the external end of said ram comprising a pair of piston and cylinder devices arranged in series with the piston of one device engageable with said ram, and the piston of the other device engageable with the first-mentioned piston, means for selectively supplying compressed gas to one or both of said devices to actuate the same, a pump having its discharge side connected to said hydraulic cylinder for charging the same, electrically actuated means responsive to the position of said ram for automatically actuating said pump when the volume of hydraulic fluid in said hydraulic cylinder reaches a predetermined minimum value, and means responsive to the position of said ram for automatically deenergizing said electrically actuated means when the volume of hydraulic fluid in said hydraulic cylinder reaches a predetermined maximum value.

2. A system for supplying hydraulic fluid under pressure comprising an hydraulic chamber adapted to contain a supply of said fluid, a ram in said chamber adapted to maintain a predetermined pressure on said fluid, a pair of pneumatic

cylinders arranged in series, a piston in one of said pneumatic cylinders operatively connected to said ram to apply pressure thereto, a piston in the other pneumatic cylinder operatively connected to the first-mentioned piston to apply pressure therethrough to said ram, a source of pneumatic fluid, means for selectively connecting said source to one or both of said cylinders, means for adjusting the pressure of the pneumatic fluid supplied by said source to a predetermined value, a source of hydraulic pressure fluid, means for automatically delivering hydraulic fluid from the last-mentioned source to said chamber when the volume of fluid therein reaches a predetermined minimum value, and means for automatically terminating the delivery of hydraulic fluid from the last-mentioned source when the volume of fluid in said chamber reaches a predetermined maximum value.

3. A system for supplying hydraulic fluid under pressure comprising an hydraulic chamber adapted to supply said fluid, a ram in said chamber adapted to maintain a predetermined pressure on the fluid therein, a pair of pneumatic cylinders arranged in series, a piston in one of said cylinders operatively connected to said ram to apply pressure thereto, a piston in the other pneumatic cylinder operatively connected to the first-mentioned piston to apply pressure therethrough to said ram, a source of pneumatic fluid, means for selectively connecting said source to one or both of said cylinders, means for adjusting the pressure of the pneumatic fluid supplied by said source to a predetermined value, means responsive to the position of said ram for automatically delivering hydraulic pressure fluid to said chamber when the volume of fluid therein reaches a predetermined minimum value, and means responsive to the position of said ram for automatically terminating the delivery of hydraulic fluid to said chamber when the volume of fluid therein reaches a predetermined maximum value.

4. A system for supplying hydraulic fluid under pressure comprising an hydraulic chamber adapted to supply said fluid, a ram in said chamber adapted to maintain a predetermined pressure on the fluid therein, a pneumatic cylinder, a piston therein operatively connected to said ram to apply pressure thereto, a source of pneumatic fluid connected to said cylinder, means for adjusting the pressure of the pneumatic fluid supplied by said source to a predetermined value, means for automatically delivering hydraulic fluid to said chamber when the volume of fluid therein reaches a predetermined minimum value, and means for automatically terminating delivery of hydraulic fluid to said chamber when the volume of fluid therein reaches a predetermined maximum value.

5. A system for supplying hydraulic fluid under pressure comprising an hydraulic chamber adapted to supply said fluid, a ram in said chamber adapted to maintain a predetermined pressure on said fluid, means for developing a predetermined pressure against said ram comprising a pneumatic device, a source of pneumatic fluid under a predetermined pressure operatively connected to said device, means for automatically recharging said chamber, comprising means responsive to the position of said ram for automatically delivering hydraulic fluid to said chamber when the volume of fluid therein reaches a predetermined minimum value, and means responsive to the position of said ram for automatically terminating delivery of fluid to said chamber when the volume

of fluid therein reaches a predetermined maximum value.

6. An hydraulic system for supplying hydraulic fluid under a predetermined pressure value comprising an hydraulic cylinder, a ram therein, means for developing pressure against the external end of said ram comprising a plurality of piston and cylinder devices arranged in series with the respective pistons engageable with each other, means for selectively supplying compressed gas to one or a plurality of said devices to actuate the same against said ram, a source of hydraulic fluid under pressure greater than that exerted against said ram during actuation of all of said devices, said source being connected to said cylinder through one-way valve means accommodating flow of fluid to said cylinder, means for terminating flow of fluid from said source when the ram has been urged to its retracted position against the resistance of the first-mentioned means, and a supply line connected to said cylinder at the downstream side of said valve means for supplying fluid under pressure from said cylinder.

7. A system for supplying hydraulic fluid under pressure comprising an hydraulic cylinder, a ram therein, another cylinder containing a body of compressed gas, a piston in said other cylinder urged by said gas against said ram to exert pressure on the hydraulic fluid in said hydraulic cylinder, a source of hydraulic fluid under pressure greater than that exerted on said ram by said piston, said source being connected to said hydraulic cylinder through one-way valve means accommodating flow of fluid to said hydraulic cylinder, and a line connected to said hydraulic cylinder for supplying hydraulic fluid therefrom.

8. A system, according to claim 7, wherein means are provided for automatically interrupting flow of hydraulic fluid from said source when the volume of fluid in said hydraulic cylinder reaches a predetermined maximum value, and means are provided for automatically effecting flow of fluid from said source to said hydraulic cylinder when the volume of fluid therein reaches a predetermined minimum value.

9. An hydraulic system for supplying hydraulic fluid under a predetermined pressure value comprising an hydraulic cylinder, a ram therein, a pair of air cylinders, pistons in respective air cylinders arranged in series with one piston engaging the ram and the other piston adapted when actuated by air in its cylinder to engage said one piston, means for selectively supplying compressed air to one or both air cylinders, and a supply line connected to said hydraulic cylinder through a one-way check valve accommodating flow of hydraulic fluid from said hydraulic cylinder, said line being adapted to supply said fluid.

10. A system, according to claim 9, wherein condition responsive means are provided for supplying pressure fluid to said hydraulic cylinder when the volume of fluid therein reaches a pre-

determined minimum value, and condition responsive means are provided for automatically terminating the supplying of pressure fluid to said hydraulic cylinder when the volume of fluid therein reaches a predetermined maximum value.

11. A system for supplying hydraulic fluid under a predetermined adjustable pressure comprising an hydraulic cylinder, a ram therein, a plurality of compressed gas piston and cylinder devices arranged with their pistons in series with each other and with said ram, means for selectively delivering pressure gas to one or more of said devices for actuation thereof, and a line connected to said hydraulic cylinder for delivering the fluid therefrom.

12. A system, according to claim 11, wherein means are provided for automatically recharging said cylinder when the volume of fluid therein reaches a predetermined minimum value, and means are provided for rendering the first-mentioned means ineffective when the volume of fluid in said hydraulic cylinder reaches a predetermined maximum value.

13. A system for supplying hydraulic fluid under a predetermined adjustable pressure comprising an hydraulic cylinder, a ram therein, a plurality of fluid pressure piston and cylinder devices arranged with their pistons in series with each other and with said ram, means for selectively delivering pressure fluid to one or more of said devices for actuation thereof, and a line connected to the hydraulic cylinder for delivering hydraulic fluid therefrom.

14. A system for supplying hydraulic fluid under pressure comprising an hydraulic chamber adapted to contain said fluid, a ram in said chamber adapted to maintain a predetermined pressure on the fluid therein, a cylinder adapted to contain pressure fluid of a different character, a piston in said cylinder operably connected to said ram to apply pressure thereto, a source of said second-mentioned fluid connected to said cylinder for delivering said second-mentioned fluid, thereto, means for automatically delivering hydraulic fluid to said chamber when the volume of hydraulic fluid therein reaches a predetermined minimum value, and means for automatically terminating delivery of hydraulic fluid to said chamber when the volume of hydraulic fluid therein reaches a predetermined maximum value.
